H. Dexter

Design for Statue of Gen'l Warren

Patented Aug. 4. 1857.

Des 919

Henry Dexter, of Cambridge, Mass.

Assignor to

William Carlton, of Charlestown, Mass

Letters Patent No 919. Dated Aug. 4. 1857

The Schedule referred to in these Letters Patent and making part of the same

To all whom it may concern

Be it known that I, Henry Dexter, of Cambridge in the County of Middlesex and State of Massachusetts, have invented or produced a new and original design for a Statue of General Warren, of which the following is a description, reference being had to the accompanying Photographs taken from the Statue.

The said Photographs represent a Statue of General Warren of full length, with military boots and military frock coat, the vest buttoned up at the throat; with the left foot slightly advanced, the left hand in a position crossing the body, the right hand resting on the hilt of a sword the point of which rests on a pedestal. The figure is represented without a hat, with the hair curled at the sides of the head.
